FOREIGN PATENT DOCUMENTS

WO 2015-099532 A1 7/2015

Primary Examiner — Barbara Fox*Assistant Examiner* — Mary Shannon Malley(74) *Attorney, Agent, or Firm* — LaBatt, LLC(57) **CLAIM**

The ornamental design for a pivot tab, as shown and described.

DESCRIPTION

FIG. 1 is a perspective view of a pivot tab according to the present design.

FIG. 2 is a front view of the pivot tab shown in FIG. 1.

FIG. 3 is a rear view of the pivot tab shown in FIG. 1.

FIG. 4 is a top plan view of the pivot tab shown in FIG. 1. FIG. 5 is a bottom view of the pivot tab shown in FIG. 1; and,

FIG. 6 is a right side elevation view of the pivot tab shown in FIG. 1, the left side elevation view being a mirror image thereof.

The dashed broken lines illustrate portions of the pivot tab that form no part of the claimed design. The dot-dash broken lines illustrate a boundary between claimed and unclaimed features and form no part of the claimed design.

1 Claim, 6 Drawing Sheets(56)
